(57) **CLAIM**

I claim the ornamental design for blind with honeycomb structure, as shown in the accompanying drawings.

DESCRIPTION

FIG. 1 is a perspective view of a blind with honeycomb structure showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof;

FIG. 7 is a rear elevational view thereof;

FIG. 8 is a perspective view thereof in application to a honeycomb blind, wherein environmental structures illustrated by broken lines form no part of the claimed design.

FIG. 9 is a perspective view thereof in a folded situation; and, FIG. 10 is a perspective view of the honeycomb blind thereof in a folded situation, wherein environmental structures illustrated by broken lines form no part of the claimed design.
